CLAIM

The ornamental design for a cushion for supporting the patients head as shown and described.

DESCRIPTION

1.1 is a top view of a cushion for supporting the patient's head according to the design;

1.2 is a front view of the cushion for supporting the patient's head of 1.1;

1.3 is a right side view of the cushion for supporting the patient's head of 1.1, a left side view thereof being a mirror image of the right side view; and

1.4 is a perspective view of the cushion for supporting the patient's head of 1.1.

The portions of the design shown in black form no part of the claimed design.
